UNITED STATES PATENT OFFICE.

CHARLES WILTSIRE WOOD, OF FAIRMOUNT, NEW JERSEY.

DESIGN FOR A GAME-BOARD.

SPECIFICATION forming part of Design No. 27,789, dated October 26, 1897.

Application filed July 29, 1897. Serial No. 646,429. Term of patent 14 years.

To all whom it may concern:

Be it known that I, CHARLES WILTSIRE WOOD, a citizen of the United States, residing at Fairmount, in the county of Hunterdon and State of New Jersey, have invented a new and useful Design for a Game-Board, of which the following is a full, clear, and exact description.

The board shown in the drawings forming part of this specification is one which I have designed for a new game invented by myself and played somewhat as in Crokinole, by snapping the men or counters from point to point thereon.

Referring to the said drawings, in which Figure 1 is a view thereof upon a reduced scale and Fig. 2 is a cross-section thereof, it will be seen that the board is substantially square in contour and surrounded by a border slightly raised above the field of the board for the purpose of preventing the counters from passing beyond the margin thereof.

My game-board is preferably about sixteen inches in length upon each side, and just within the said border A is a margin B of two inches in width passing about the entire board A. Upon two opposite sides of the

field are the series of small squares C, each about equal in size to the counter used in the game. These I term the "base-goals." Centrally between these base-goals C are two central goals D, the spaces between these central goals and base-goals being termed "field-spaces." I usually have the base-goals 35 C and the nearer center goal D of the same color, as scarlet. The other center goal and base-goals will be of some other color, as Nile green, while the fields E and the margin B will be of some different color still—such, 40 for instance, as pearl-gray. This color scheme is indicated in Fig. 1 by vertical lines for the scarlet, horizontal for the green, and blank spaces for the gray.

What I claim as my invention, and desire 45 to secure by Letters Patent, is as follows, to-wit:

The design for game-boards herein shown and described.

In testimony that I claim the foregoing invention I have hereunto set my hand and seal this 30th day of June, in the year 1897.

CHARLES WILTSIRE WOOD. [L. s.]
